UNITED STATES PATENT OFFICE

2,489,830

SCRIBE HOLDING RULER

Guthrie B. Stone, Springwater, N. Y.

Application May 8, 1946, Serial No. 668,249

1 Claim. (Cl. 33—42)

1

This invention relates to new and useful improvements and structural refinements in straight edges for try-squares, and the principal object of the invention is to provide a device of the character herein described, which will substantially decrease the utility of conventional try-squares by providing the same with a marking instrument.

A further object of the invention is to provide a straight edge which is adapted to receive any one of a plurality of marking instruments, such as may assume the form of pencils, scribes, glass cutters and the like.

Another object of the invention is to provide a straight edge in which the marking instruments are readily interchangeable and which, as a whole, may be easily applied to or removed from the try-square.

An additional object of the invention is to provide a marking device which does not, in any way, interfere with the conventional operation of the straight edge and square.

A still further object of the invention is to provide a straight edge which is simple in construction and which will readily lend itself to economic manufacture.

With the above more important objects in view, and such other objects as may become apparent as this specification proceeds, the invention consists essentially of the arrangement and construction of parts as illustrated in the accompanying drawings, in which—

Figure 1 is a developed view of the straight edge forming blade,

Figure 2 is a top plan view of the invention,

Figure 3 is a side elevation thereof,

Figure 4 is a top plan view, illustrating the invention in association with a try-square,

Figure 5 is an end view of the invention, and

Figure 6 is an elevational view of a marking instrument used in the invention.

Like characters of reference are used to designate like parts in the specification and throughout the several views.

Referring now to the accompanying drawings in detail, the invention embodies in its construction a blade 10, provided with the conventional graduations 11 and being formed at one end thereof with an integral extension 12, configured substantially as shown.

2

The extension 12 is angulated and arcuated to provide a substantially tubular socket 13, this being accomplished by bending the extension upwardly from the phantom line 14 and twisting the portion 15 of the extension 12, as is best shown in Figures 3 and 5. The substantially square portion 16 of the extension is then arcuated as shown, to provide the substantially tubular body portion of the socket 13.

10 It will be noted that the socket is disposed on one side of the blade 10 and extends in a perpendicular relationship with respect thereto. Furthermore, the longitudinal axis of the socket 13 lies in the plane of the adjacent end 17 of the 15 blade, from which end the graduations 11 are calibrated.

The marking instrument 18 may assume the form of a pencil, a glass cutter, a scribe, or the like, and is slidably receivable in the socket 13. 20 A suitable set-screw 19, positioned in the side of the socket and engaging the instrument 18, is employed for releasably retaining the instrument in position.

It will be noted that since the axis of the socket 25 13 lies in the plane of the end 17, as aforesaid, the pointed extremity 20 of the instrument 18 will coincide with the end 17 and hence, with the "0" of the graduated scale 11.

The remaining side of the blade 10 is provided 30 with a suitable, longitudinally extending groove 21, this coating with the conventional try-square 22, with which the invention may be employed.

When the invention is placed in use, the square 35 22 may be adjusted upon the blade 10 with respect to the graduated scale 11, whereupon the marking instrument 18 may be employed for inscribing the required lines on the work. It is believed that the various applications for which the invention may be employed will be clearly apparent from the foregoing disclosure and accordingly, further description thereof at this point is considered unnecessary.

While in the foregoing there has been shown 45 and described the preferred embodiment of this invention it is to be understood that minor changes in the details of construction, combination, and arrangement of parts may be resorted to without departing from the spirit and scope of the invention as claimed.

What I claim as my invention is:

A scribe holding ruler, comprising a blade having an end edge of a lesser dimension than the width of said blade, a strap-like extension formed integrally with said blade at one side of said end edge, and a plate formed integrally with said extension and having substantially the width of said blade, said extension being upturned and axially twisted, said plate being arcuated and forming a substantially tubular scribe receiving socket, and the axis of said socket being disposed in the plane of said edge.

GUTHRIE B. STONE.
